UNITED STATES PATENT OFFICE.

ROBERT CAMPBELL CREELMAN, OF BAKER, BRITISH COLUMBIA, CANADA.

GATE LOCK.

Application filed June 20, 1925. Serial No. 38,510.

The present invention relates to a gate lock and has for its principal object to provide a device of this nature which is simple in construction, efficient and reliable in operation, easy to manipulate, strong, durable, and well adapted to the purpose for which it is designed.

With the above and numerous other objects in view as will appear as the description proceeds, the invention resides in certain novel features of construction, and in the combination and arrangement of parts as will be hereinafter more fully described and claimed.

15 In the drawing:—

Figure 1 is a fragmentary elevation of a gate showing particularly the lower portion thereof with my locking mechanism associated therewith, and

20 Figure 2 is a horizontal section taken therethrough showing the locking mechanism in top plan.

Referring to the drawing in detail it will be seen that 1 designates a gate of any preferred construction, being herein shown as an ordinary picket gate, and I provide an elongated opening 2 extending inwardly from the free edge of the gate adjacent its bottom. A bar 3 is disposed in the entrance of the opening 2 extending horizontally and transversely of the gate, being supported by a suitable bracket 4. An elongated bolt 5 is slidable through the center of the bar 3 and also through a bracket 6 carried by the gate 1 at the inner portions of the opening 2. A pair of links 7 are pivoted to the bar 3, one at each end thereof. A pair of links 8 are pivoted to the bolt 5 intermediate its ends and one link 8 is pivoted to the adjacent link 7 as at 9. A bowed spring 10 has its ends fixed to the links 8 as at 11 and urges the points 9 away from each other so as to normally dispose the end of the bolt 5 beyond the free end of the gate for engagement with a suitable keeper 13. By pushing either of the pivot points 9 inwardly toward the gate it will be seen that the bolt 5 may be slid toward the pivoted end of the gate out of engagement with the keeper 13.

25 With a gate having the locking mechanism above described incorporated therein, it is possible for a person with a handful of bundles to approach the gate and give one of the pivot points 9 a kick, thus releasing the bolt from the keeper so that the gate

may be easily opened. When the gate is swung toward a closed position, the keeper will be automatically engaged by the bolt 5 as is evident. It will be apparent from the above that I have devised a very simple and efficient locking mechanism for gates which will prove both efficient and reliable in operation. The present embodiment of the invention which I have described in detail by way of example attains all the features of advantage enumerated as desirable in the statement and description of the invention, but it is desired to point out that numerous changes in the details of construction, in the proportions, and in the combination and arrangement of parts may be resorted to without departing from the spirit or scope of the invention as hereinafter claimed or sacrificing any of its advantages.

Having thus described the invention, what I claim as new is:—

1. A locking mechanism of the class described including a bar, a pair of links pivoted to the ends of the bar, a pair of links one pivoted to each of the first mentioned links, a bolt slidable through the bar and pivotally engaged at an intermediate point to the ends of the second mentioned links whereby the pivots between the first and second mentioned links may be moved for sliding the bolt through the bar.

2. A locking mechanism of the class described including a bar, a pair of links pivoted to the ends of the bar, a pair of links, one pivoted to each of the first mentioned links, a bolt slidable through the bar and pivotally engaged at an intermediate point to the ends of the second mentioned links whereby the pivots between the first and second mentioned links may be moved for sliding the bolt through the bar, and spring means associated with the links for holding the bolt in a normal predetermined position.

3. In a locking mechanism of the class described, a bar, a bolt slidable through the bar transversely thereof, a pair of links, one pivoted to each end of the bar, a second pair of links, one pivoted to each of the first mentioned links, the second mentioned links also pivoted to the bolt intermediate its ends, and a bowed spring disposed between the second pair of links for holding the bolt in a normal predetermined position.

In testimony whereof I affix my signature.
ROBERT CAMPBELL CREELMAN.
